UNITED STATES PATENT OFFICE.

JONATHAN PETERSON, OF BROOKLYN, NEW YORK.

METHOD AND APPARATUS FOR PRODUCING COMPOUND SHEETS.

1,137,279.

Specification of Letters Patent.

Patented Apr. 27, 1915.

Application filed August 3, 1914. Serial No. 854,778.

To all whom it may concern:

Be it known that I, JONATHAN PETERSON, a citizen of the United States, residing at Brooklyn, in the county of Kings and State of New York, have invented new and useful Improvements in the Method and Apparatus for Producing Compound Sheets, of which the following is a specification.

This invention relates to a method of and apparatus for producing compound sheets, and while these improvements are useful for forming compound sheets of different kinds and for different purposes, I have illustrated the improvements as applied to the production of compound sheets which are particularly useful for forming pouches or containers for an article of manufacture such as tobacco.

A principal object of this invention is to provide an arrangement whereby a compound sheet may be produced in a very simple manner and in the form of a compound web which can be kept in the form of a roll until it is to be used. When it is to be used, the compound web is drawn from its roll and cut into sheets or blanks from which any article such as pouches or containers may be formed.

In the present instance, the pouches are intended to contain tobacco and it is desirable that the wall of such a pouch or container should be substantially impervious to moisture and the pouch as a whole substantially air-tight.

A further object of the invention is to provide a method and apparatus particularly adapted for forming a compound sheet or web embodying a metallic foil treated so that when the pouches are formed they can be readily sealed and so that the wall of the pouch will be substantially impervious to moisture.

A further object of the invention is to provide a method of and apparatus for providing the compound sheet with coatings having special properties which facilitate the formation of the compound sheet and which also facilitate the formation of a sealed package from the blanks cut from the sheet.

A further object of the invention is to provide a method and apparatus in the operation of which the coating which causes the union of the plies of the compound web or compound sheet coheres under pressure when in a dry state, in this way avoiding

the difficulties which arise where a moist adhesive is employed to join the sheets; such pressure when applied to a moist adhesive, tends to squeeze the adhesive out between the layers or webs and this tends to interfere with the efficient operation of the apparatus.

The invention resides in the method, and in the apparatus.

The invention in the apparatus consists in the general combination of parts and simplicity of detail hereinafter described, all of which contribute to produce efficient apparatus for producing compound sheets.

The invention in the method consists in those steps and combinations of steps and features to be described hereinafter, and which contribute to produce an efficient method for forming the compound sheets.

The preferred embodiment of my invention will be particularly described in the following specification while the broad scope of my invention will be pointed out in the appended claims.

In the drawings: Figure 1 is a diagrammatic view showing the apparatus partly in side elevation and partly in section, certain parts being illustrated in dotted lines. Fig. 2 is a vertical section taken through a reservoir or holder for a supply of a compound

which I prefer to use for coating the plies or webs which I combine to form the compound sheet. Fig. 3 is a plan of the reservoir shown in Fig. 2, certain parts being broken away and others shown in section. Fig. 4 is a vertical section taken about on the line 4—4 of Fig. 3, and further illustrating details of the apparatus. Fig. 5 is a side elevation illustrating another device for applying a compound to the sheet as it is being formed. Fig. 6 is a plan of parts shown in Fig. 5. Fig. 7 is a cross section taken about on the line 7—7 of Fig. 1 and illustrating the preferred means for drying the coatings which I apply to the web. Fig. 8 is a cross section taken on about the line 8—8 of Fig.

1 and illustrating the preferred means for drying the coating which is applied by the device shown in Fig. 5. Fig. 9 is a perspective showing a portion of the complete compound web. Fig. 10 is a cross section illustrating the compound web or sheet.

In carrying out my invention, I prefer to provide means for advancing a plurality of webs superposed one upon the other, the adjacent faces of the said webs being coated with a substance which is adhesive when

moist, and which has highly cohesive properties when dry.

In the present instance, one of these webs is composed of a frail metallic foil such as 5 a tin foil and I employ a single backing web of paper or similar material which I unite to the foil. For this purpose, I prefer to provide an elongated table 11 along the upper surface of which I guide the upper run 10 12 of an endless carrier belt 13 the loops of which belt pass around guide pulleys 14 at the ends of the table. On the under run of this belt I may provide pulleys 15 for additionally guiding the belt and for tightening 15 the same as will be readily understood. The upper run of this belt lies flat on the table and by any suitable means the belt may be driven slowly in the direction of the arrow indicated in Fig. 1. Belt 12 is preferably 20 of rubber.

At a convenient point preferably at the left end of the table, as indicated in Fig. 1, I provide means for supporting a supply, such as a roll 16, of foil, said foil being in 25 the form of a web 18 which is drawn out around guide pulleys 17 and extended along the table so that it is superposed upon the belt 12 the other end of the said web being coiled into a roll 19 on a suitable arbor 20. 30 This web 18 of foil is preferably of slightly greater width than the belt 12 and the table 11 so that the margins 21 of the foil web project beyond the edges of the belt in some such manner as illustrated in Fig. 7, the foil 35 web being preferably substantially centrally disposed on the belt so that these margins are of equal width.

As the belt advances, I prefer to coat the foil 18 on its upper face with a special compound which has the property of being 40 highly cohesive when dry, for this purpose, I prefer to employ a compound consisting of rubber compound which is in a pasty or viscous condition when moist, in which condition it is applied to the foil.

In order to apply the compound, I prefer to provide near the left end of the table a reservoir or holder 22 in which the compound 45 23 is placed; as this compound is of a pasty and viscous nature, it is unnecessary to confine it on all sides, hence I simply provide an open hopper having a transverse vertical wall 24 and side walls 25, said wall 24 being disposed on the side of the hopper 50 toward which the belt and foil pass.

As the belt 12 advances it carries the foil 18 through the bottom of the hopper; in Fig. 2 the uncoated foil is indicated at 18 as it passes into the hopper, and the coated foil 55 is indicated at 18 beyond the hopper. At this point, a bottom plate 27 is provided which connects the side rails 11^a of the table. Near one end of this plate, as indicated in Fig. 2, two oppositely disposed pins 27^a are provided which are for the purpose of

holding in position an upper plate or "floating" plate 28. This plate 28 is very thin, preferably $\frac{1}{16}$ inch in thickness and it is formed with projecting forks 28^a which have openings received loosely over the pins 27^a. 70 The belt 12 passes between this plate 28 and the bottom plate. The top plate 28 supports the reservoir 25 and the compound 23. The plate 28 is provided on its upper face with two pockets 29 near its side edges and these 75 pockets are for the purpose of accumulating the compound in order to smear it upon the lower sides of the margins of the foil 18, it being understood that the foil 18 passes on the upper side of the top plate 28. In this 80 way the plate 28 "floats" between the belt and the foil web, and prevents the belt from becoming smeared with the compound.

In order to facilitate the separation of the foil web from the belt as it advances, the 85 forward or first edge 28^a of the plate 28 which is engaged by the advancing web is brought to a knife edge. The other edge 28^b of this plate is also brought to a knife edge to facilitate guiding the foil back onto the 90 belt.

In the drawing the thickness of the belt 12 and web 50 and foil 18 are represented greatly magnified for the sake of clearness. It is understood however, that the foil and 95 backing web are about as thin as an ordinary sheet of paper.

The wall 24 does not extend down as far as the table so that an opening 30 is formed at this point through which the belt passes. 100 Adjacent to this opening there is provided a wiper 31 preferably in the form of a doubled sheet of felt or similar flexible material which is attached to the lower edge of an adjusting plate 32. This plate 32 tends 105 to swing toward the wall 24 by a spring connection 33 at its upper edge and may be adjusted away from the wall by a set screw 34. By screwing in the set screw 34, the amount of compound which is smeared onto 110 the foil is increased and vice versa.

The ends of this wiper 31 extend over the pockets 29 and the wiper is the full width of the foil so that as the foil passes under the hopper its upper surface is 115 completely covered with the compound, and furthermore, by reason of the fact that the compound collects in the pockets 29, the projecting margins 21 of the foil are coated on their under sides.

The reservoir 22 may be supplied from a small tank or mixer 35 directly over the reservoir and provided with a stirring device the shaft 36 of which is driven by a belt 37 which keeps the rubber compound 120 properly mixed. When desired a quantity of the rubber compound may be permitted to flow into the hopper by opening the valve 38.

I permit the coatings on the foil to dry 130

- before uniting this sheet with the other sheet or web. In order to accomplish this, the table 11 may be very long so as to give time for the moist compound to dry; however, I prefer to dry the coatings artificially, for which purpose I prefer to provide on the upper side of the table an air blast device preferably in the form of a longitudinally disposed air pipe 39, said air pipe having a plurality of orifices 40 on its under face which direct an air blast down onto the upper face of the coated foil, and in order to dry the coatings on the under side of the margins 21, I prefer to provide a similar air blast device in the form of pipes 41 which extend along the sides of the table and which have openings 42 for directing an air blast onto the under side of the margins.
- 10 20 In order to prevent any dislocation of the foil on the belt by reason of these air blasts and also to produce a high adhesion between the foil and the belt in order to relieve the foil, so far as possible, of tension throughout its length, and assist in drawing the same forward I prefer to moisten the belt 13; for this purpose I prefer to provide a sprinkling device 43 preferably disposed at the left loop of the belt and arranged to spray water 30 against the under run or outer surface of the belt, as indicated, the spray water being carried off by a suitable drain 44.
- Adjacent the reservoir 22 I provide a guide 45 for the foil, said guide preferably 35 consisting of a transverse plate having extensions 46 bent downwardly so as to lie near the side edges of the foil. The hopper or reservoir 22 is preferably supported movably by means of brackets 47 and has projecting gudgeons 48 which are received in the brackets, as indicated most clearly in Fig. 3. The reservoir 22 tends to tilt by gravity on the axis of its gudgeons downwardly toward the wiper 31 which keeps 45 the wiper in contact with the foil.
- I provide means for guiding another web or backing sheet along over the foil web. For this purpose I prefer to provide a roll 49 which carries the backing sheet in the 50 form of a web 50 which is drawn out and passes around the roller 14 and onto the roll 19. Preferably near the roll 49 I provide two presser rollers 51 and 52 the former of which is disposed above the table and 55 the latter of which is disposed below the table. The web 50 which forms the roll 49 is preferably coated on one side with a compound which is highly cohesive when dry, preferably the said compound 23. The web 60 50 is extended so that its coated side comes against the coated face of the foil web 18, as the two webs pass between the rollers 51 and 52 they are forcibly pressed together by the faces of the rolls so that the coating 65 on the web 50 coheres to the coating on the web 18. This web 50 is preferably centrally superposed over the foil web and is of less width than the foil web so that the compound web or sheet formed by uniting the webs presents projecting or unbacked 70 margins of foil.
- For special reasons which arise in the formation of pouches from blanks cut from the compound web, I prefer to provide another coating of the compound on the exposed 75 margins of the backing sheet. For this purpose I prefer to provide a coating device 53 which may have the form illustrated in detail in Figs. 5 and 6. In this instance the device simply consists of a plate 54 having 80 two small wells or reservoirs 55 having openings 56 which come directly over the edges of the backing web 50. This plate 54 is supported between two arms 57 attached to a cross shaft 58 the ends of which are 85 supported in brackets 59 on the side rolls 11^a of the table. In other words, the bottom edge of the plate 54 simply rests by gravity on the upper face of the web 50 and as the web advances this results in 90 smearing a coating of the compound along the edges 50^a of the web 50. This coating on the edges 50^a I permit to dry and this will occur if the table is sufficiently long, before the compound web passes onto the 95 roll 19. However, I prefer to dry this coating artificially for which purpose I prefer to provide an air blast device which may be in the form of air pipes 60 similar to the pipes 39 and 41. The arrangement of these 100 pipes is illustrated in Figs. 1 and 8, and they have orifices 61 on their under side which direct the air currents down on the coated edges 50^a.
- On account of the fact that the coating 105 compound employed is highly cohesive under pressure, I provide means for preventing the cohesion of the projecting margins of the compound sheet which is formed into a roll 19. For this purpose I prefer to provide, near the roll 19, a supporting arbor 62 for a supply roll 63 consisting of a protecting sheet or web 64 which is extended from the roll 63 and wrapped on the roll 19 simultaneously with the compound web. This 110 protecting sheet 64 is as wide or wider than the compound sheet so that the coated edges of the foil cannot come in contact with each other. It also protects the flimsy projecting foil margins from injury. It should be 115 noted however, that this protecting sheet is not for the purpose of preventing the backed portions of the compound sheet from adhering to each other because the compound does not have adhesive properties 120 when dry, and in order to bring about the union of two webs such as described, both the webs must be coated with the compound.
- 125 Special attention is called to the fact that when the webs pass between the rollers 51 130

and 52 their coatings are in a dry state and hence there is no tendency to squeeze out the coatings and smear the adjacent parts of the apparatus with the compound. This arrangement results in producing a compound sheet of very uniform qualities.

The web may be printed upon so as to form labels 65, before it is formed into a supply roll as roll 49 and the printing on these labels may be alternately reversed as illustrated in Fig. 9. When the web is being fed into a pouch forming machine, the machine cuts the web on transverse lines 66 so as to form blanks with reversed labels; these blanks are then folded on the lines 67 so that the zone 68 between the lines 67 forms the bottom or lower end of the pouch. The projecting margins 69, of the blank are then folded upon each other so that the coatings of the overlapping margins come together, whereupon simply by pressure, the coatings cohere and unite the parts of the seam so as to form a substantially air-tight connection.

Special attention is called to the feature of forming a compound sheet into a roll from which the material is delivered directly into the pouch forming machine. This arrangement avoids the necessity of feeding small blanks individually into the pouch forming machine. On account of the foil embodied in these blanks they are handled with difficulty by machinery; however, when they are in the form of a roll they can be drawn as a web into the pouch forming machine which cuts the blank from the web at the instant that the pouch is to be formed.

It is understood that the embodiment of my invention as described above is only one of the many embodiments or forms the invention may take and I do not wish to be limited in the practice of my invention either in the process product or apparatus, nor in my claims to the process product or apparatus to the particular embodiment set forth.

What I claim is:

1. The method of forming a compound sheet which consists in advancing a continuous web, applying a moist dryly cohesive compound coating to the face of said web, drying said coating, advancing a second continuous web superposed over said first web and having a face with a dry coating of the said compound, arranged with the coated faces of said webs adjacent to each other, and then pressing said webs together while said coatings are dry to unite said webs by the dry cohesion of said coatings.

2. The method of forming a compound sheet which consists in advancing a continuous web of foil, applying a moist dryly cohesive compound coating to the face of said web, drying said coating, advancing a continuous backing web having a face with

a dry coating of the said compound and arranged to overlie said foil web, with the coated faces of said webs adjacent to each other, and then pressing said webs together while said coatings are dry to unite said webs by the dry cohesion of said coatings.

3. The method of forming a compound sheet which consists in advancing a continuous web of foil, covering one face of said foil web with a moist dryly cohesive compound coating, applying said moist compound coating to the margins of said foil web on the other face thereof, advancing a continuous backing web having a face with a coating of said compound and arranged to overlie substantially centrally said foil web whereby the said coated margins are left unbacked and projecting beyond the edges of said backing sheet, drying said moist coatings, and then pressing said webs together while said coatings are dry to effect dry cohesion of their coatings and form the compound sheet.

4. The method of forming a compound sheet which consists in advancing a continuous web of foil, covering one face of said foil web with a moist dryly cohesive compound coating, applying said compound coating to the margins of said foil web on the other face thereof, advancing a continuous backing web having a face with a coating of said compound and arranged to overlie substantially centrally said foil web whereby the said coated margins are left unbacked and projecting beyond the edges of said backing sheet, drying said coatings, and then pressing said webs together while said coatings are dry to effect dry cohesion of their coatings and form the compound sheet, and applying said compound to the margins of the exposed face of said backing web.

5. The method of forming a compound sheet for producing pouches which consists in advancing a continuous web of foil, covering one face of said foil web with a moist dryly cohesive compound coating, applying said compound coating to the margins of said foil web on the other face thereof, advancing a continuous backing web having a face with a coating of said compound and arranged to overlie substantially centrally said foil web whereby the said coated margins are left unbacked and projecting beyond the edges of said backing sheet, drying said coatings, and then pressing said webs together while said coatings are dry to effect dry cohesion of their coatings and form the compound sheet, and applying said compound to the margins of the exposed face of said backing web, coiling the compound sheet into a roll, and simultaneously coiling a protecting web into the roll between the coils of the compound sheet to prevent contact between the coated coils of said projecting margins.

6. The method of forming a compound sheet for producing pouches which consists in advancing a continuous web of foil, covering one face of said foil web with a moist dryly cohesive compound coating, applying said compound coating to the margins of said foil web on the other face thereof, advancing a continuous backing web having a face with a coating of said compound and arranged to overlie substantially centrally said foil web whereby the said coated margins are left unbacked and projecting beyond the edges of said backing sheet, drying said coatings, and then pressing said webs together while said coatings are dry to effect dry cohesion of their coatings and form the compound sheet, applying said compound to the margins of the exposed face of said backing web, coiling the compound sheet into a roll, and simultaneously coiling a protecting web into the roll between the coils of the compound sheet to prevent contact between the coated coils of said projecting margins and to reinforce the said margins.

7. The method of forming a compound sheet on a continuously advancing carrier belt, which consists in advancing a carrier belt, moistening the surface of the belt, applying a web of foil to the belt so as to adhere to the moistened surface thereof, applying a moist rubber compound coating to the face of said foil web, advancing a continuous backing web having a coating of the said rubber compound and arranged to overlie said foil web with the coated faces of said webs adjacent to each other, and then uniting said webs by pressing the same together to effect the cohesion of their coatings.

8. The method of forming a compound sheet which consists in advancing a continuous web of foil, applying a moist dryly cohesive compound coating to the face of said web, drying said coating, advancing a continuous backing web having a face with a dry coating of the said compound and arranged to overlie said foil web, with the coated faces of said webs adjacent to each other, and then pressing said webs together while said coatings are dry to unite said webs by the dry cohesion of said coatings.

9. The method of forming a compound sheet which consists in advancing a continuous web of foil, applying a moist dryly cohesive rubber compound coating to the face of said web, drying said coating, advancing a continuous backing web having a face with a dry coating of said compound and arranged to overlie said foil web with the coated faces of said webs adjacent to each other, and then pressing said webs together while said coatings are dry to unite said webs by the dry cohesion of said coatings.

10. The method of forming a compound

sheet which consists in supporting a web of frail foil on a carrier web and moistening the supporting surface of the carrier to cause temporary adhesion of the foil thereto throughout its area, covering said foil web with a moist dryly cohesive compound coating, drying said coating, advancing a backing web having a dry coating of said compound arranged to overlie said foil web with the coated faces of said webs adjacent, and pressing said webs together while dry to unite the same by dry cohesion of said coatings

11. In an apparatus for forming a compound sheet, in combination, means for advancing a continuous web, means for applying thereto a coating of a dryly cohesive substance, means for artificially drying said coating, means for advancing a second web superposed over said first web, and having a dry coating of said dryly cohesive substance disposed adjacent to the coating on said first web, and means for pressing said webs together to unite the same by cohesion of said coatings in a dry state.

12. In an apparatus for forming a compound sheet, in combination, means for advancing a continuous web, means for applying thereto a moist coating of a dryly cohesive substance, means for drying said coating, means for advancing a second web superposed over said first web, and having a dry coating of said dryly cohesive substance disposed adjacent to the coating on said first web, and means for pressing said webs together to unite the same by cohesion of said coatings in a dry state.

13. In an apparatus for forming a compound sheet, in combination, means for advancing a continuous web, means for applying thereto a coating of dryly cohesive substance, means for artificially drying said coating, means for advancing a second web superposed over said first web, and having a dry coating of said dryly cohesive substance disposed adjacent to the coating on said first web, and rollers between which said web passes for pressing said webs together to unite the same by cohesion of said coatings in a dry state.

14. In an apparatus for forming a compound sheet, in combination, an endless belt conveyer arranged to support and advance a continuous web, means for applying a moist dryly cohesive coating to said web, means over said conveyer for drying said coating while advancing therewith, means for guiding a second web superposed over said first web and having a dryly cohesive coating adjacent said first web, and means for pressing said webs together while said coatings are dry to unite the same by the cohesion of said coatings.

15. In an apparatus for forming a compound sheet, in combination, an endless belt

conveyer arranged to support and advance a continuous web, means over said conveyer for applying a moist dryly cohesive coating to said web, an air blast device for drying said coating while advancing therewith, means for guiding a second web superposed over said first web and having a dryly cohesive coating adjacent said first web, and means for pressing said webs together while said coatings are dry to unite the same by the cohesion of said coatings.

16. In an apparatus for forming a compound sheet, in combination, an endless belt conveyer arranged to support and advance a continuous web of foil, means for moistening said belt to increase the adhesion of said film thereto, means over said conveyer for applying a moist dryly cohesive coating to said web, means for drying said coating while advancing therewith, means for guiding a second web superposed over said first web, and means for pressing said webs together while said coatings are dry to unite the same by the cohesion of said coatings.

17. In an apparatus for forming a compound sheet, in combination, an endless belt conveyer arranged to support and advance a continuous web, means for applying a moist dryly cohesive coating to said web, means for drying said coating, means for guiding a second web superposed over said first web and having a dryly cohesive coating adjacent said first web, means for pressing said webs together while said coatings are dry to unite the same by the cohesion of said coatings, means for applying a moist dryly cohesive coating to the margins of said second web on the upper face thereof, and means for drying said last coating.

18. In an apparatus for forming a compound sheet for producing pouches, in combination, a continuously moving carrier for supporting and advancing a web of foil, means for covering one face and the margins of the opposite face thereof with coatings consisting of a moist dryly cohesive compound, means for drying said coatings, means for guiding a backing web of narrower width than said first web superposed substantially centrally on said foil web and having a dry dryly cohesive coating of said compound, means for pressing said webs together while said coatings are dry to unite the same by the cohesion of said coatings and thereby form a compound web, means for coiling said compound web into a roll, and means for simultaneously coiling into said roll a protecting web lying between the coils of said compound web and preventing adhesion between the adjacent coils thereof.

19. In an apparatus for forming a compound sheet in combination, an endless belt conveyer, means for guiding a web of foil wider than said belt so as to be supported

and advanced by said belt, means for moistening said belt to cause adhesion of said foil thereto, means for applying moist dryly cohesive coatings respectively to the upper face of said foil web and to the under face of the margins thereof, air blast devices for directing an air current onto said coatings to dry the same, means for guiding a backing web along said belt superposed over said foil web and having a dry dryly cohesive coating adjacent said foil web, means for pressing said webs together to unite the same by the cohesion of their coatings, means for applying a moist dryly cohesive coating on the upper face of said backing web at the margins thereof, and an air blast device for drying said last named coating.

20. In an apparatus for forming a compound sheet in combination, an endless carrier belt, means for guiding a web of foil so as to lie upon said belt and be advanced thereby, a sprinkler device for sprinkling water on said belt to moisten the same and increase the adhesion of said foil thereto, a reservoir disposed over said web adapted to contain a moist dryly cohesive compound to form a coating on the upper side of said web, and having means for applying a coating of the said compound to the under side of the margins of said web, means for drying the coatings, means for guiding a backing web superposed over said foil web and having a dry dryly-cohesive coating adjacent said foil web, and means for pressing said webs together to unite the same by the cohesion of said coatings.

21. The method of forming a compound sheet on a continuously advancing carrier belt, which consists in applying a web of frail metal foil of greater width than said belt thereto so as to be supported and advanced by said belt and disposed centrally on said belt whereby the margins of said foil web project beyond the edges of said belt, applying a moist coating to the under side of the projecting margins of said foil, blowing air upon said moist coating to dry the same while said foil web is supported by said belt, and moistening said belt to cause adhesion between the foil and said belt to prevent dislocation of said foil web by the air blast.

22. In an apparatus for forming a compound sheet, in combination, an endless belt conveyer, means for guiding a web of foil of greater width than said belt so as to be supported and advanced by said belt and disposed centrally upon said belt so that the margins of said foil web project beyond the edges of said belt, means for applying a moist coating to the under side of the said margins of said foil web, means for directing an air blast upon said coated margins to dry said coating, and means for moistening

said conveyer belt to cause temporary adhesion of said foil web and prevent dislocation thereof by said air blast.

23. In apparatus for forming a compound sheet, in combination, an endless belt conveyer, means for guiding a web so as to be advanced by said belt, means for applying a compound to the upper face of said web as the belt advances, and means disposed between the belt and the web for preventing the application of said compound to said belt.

24. In apparatus for forming a compound sheet, in combination, an endless belt conveyer, means for guiding a web so as to be advanced by said belt, means for applying a compound to the upper face of said web as the belt advances, and means disposed between the belt and the web for preventing the application of said compound to said belt, means for guiding another web onto said first web, and means for pressing the same together.

25. In apparatus for forming a compound sheet, in combination, an endless belt conveyer, means for guiding a web so as to be

advanced by said belt, means for applying a compound to the upper face of said web as the belt advances, and a plate disposed between the belt and the web for preventing the application of said compound to said belt, said plate being fixed against longitudinal movement.

26. In apparatus for forming a compound sheet, in combination, an endless belt conveyer, means for guiding a web so as to be advanced by said belt, means for applying a compound to the upper face of said web as the belt advances, and a plate disposed between the belt and the web for preventing the application of said compound to said belt, said plate having pockets in the upper face thereof for collecting said compound to smear the same on the under side of said web.

In testimony whereof I have hereunto set my hand in presence of two subscribing witnesses.

JONATHAN PETERSON.
